UNITED STATES PATENT OFFICE.

FREDERICK G. WIELAND, OF BROOKLYN, NEW YORK, ASSIGNEE TO ANCHOR CAP & CLOSURE CORPORATION, OF BROOKLYN, NEW YORK, A CORPORATION OF NEW YORK.

SCREW-CAP.

Specification of Letters Patent. Patented Jan. 6, 1920.

1,327,453.

Application filed February 27, 1919. Serial No. 279,498.

To all whom it may concern:

Be it known that I, FREDERICK G. WIELAND, a citizen of the United States, residing at Brooklyn, in the county of Kings, State of New York, have invented certain new and useful Improvements in Screw-Caps, of which the following is a specification.

This invention relates broadly to bottle and jar closures and more specially to screw caps.

The principal object of this invention is to provide an exceptionally strong and stable closure of the screw cap type, suitable for use on containers having either screw threads or inclined lugs, and wherein the exterior of the cap is symmetrical and regular, and with the screw engaging lugs substantially invisible from the exterior of the cap when the cap is in position on a suitable container.

A further object of the present invention is a screw cap of the character specified and wherein the thread engaging lugs are formed adjacent the wire or rolled edge of the cap and with the metal in the lugs under compression in such manner that the lugs are rigid and substantially non-yielding.

A still further and important object of the present invention is a cap of the character specified wherein the thread engaging faces of the lugs are substantially at right-angles to the skirt of the cap and comprise metal under compression forces and supported directly by the wire or rolled edge of the cap.

Another object of my invention is a screw cap which has excess metal in the skirt portion compressed inwardly thereacross to form inwardly directed thread engaging lugs.

A further object is the provision of a cap as specified and wherein the edge of the cap is rolled adjacent the said lugs in order to provide a supporting wire edge effective to prevent stripping the lugs over the threads on the container.

A still further object is the provision of a screw cap wherein excess metal is provided at intervals adjacent the lower portion of the skirt, and said excess metal compressed inwardly and partially folded upon

itself to provide inwardly extending tubular projections which reinforce the skirt. 55

Another object of the present invention is a cap of the character specified wherein projections are formed at suitable intervals around the lower edge of the cap from metal folded upon itself and with the projections comprising a portion contiguous to the inner edge of the wire roll and without collapsing the wire roll.

Other and further objects of the present invention will in part be obvious and will 65 in part be pointed out hereinafter in the specification following by reference to the accompanying drawings forming a part of the application.

Figure 1 is a view of the blank from 70 which the cap is formed and illustrates the excess metal from which the thread engaging projections are made.

Fig. 2 is a perspective view showing the 75 inside of the blank after it leaves the press which has formed the skirt of the cap.

Fig. 3 is a more or less diagrammatical view of one form of mechanism adaptable to form the projections from the excess metal specified. 80

Fig. 4 is a view illustrating the inside 85 of the cap blank after it has left the mechanism illustrated in Fig. 3, and shows the screw-threading projections after having been completely formed.

Fig. 5 is a section on line A—B of Fig. 4.

Fig. 6 is a plan view looking at the inside of a completely finished cap.

Fig. 7 is a section taken on line C—D of Fig. 6. 90

Fig. 8 is a perspective view showing the exterior of the completed cap.

Fig. 9 is a detail sectional view taken on line E—F of Fig. 6.

Heretofore in the art there have been 95 three general forms of screw caps. The first has spiral threads in the skirt of the cap so that complete screw-threads are carried by the cap. The other two forms of screw caps are of the sort known as "quick- 100 thread" caps. One way of making this latter group has comprised the indenting of the skirt of the cap at intervals to provide lugs adapted to engage suitable threads on a container. The other way of making the 105 "quick-thread" type of cap has comprised the

striking up of small lugs by bending inward the edge of the skirt. In some cases the raw edge of the skirt is bent inwardly, in other cases wire rolled edges are flattened and bent inward.

The first type of screw cap specified is a satisfactory cap for many purposes but requires a longer time for the seating operation than does the "quick-thread" type cap.

- 10 The "quick-thread" type caps heretofore mentioned are more or less unsightly because the striking up or bending in of the metal breaks the symmetry of the cap. Furthermore, the engaging lugs are so local in 15 the transmission of forces to the skirt of the cap that it often happens in tightening such a cap the lugs will spring out and jump over or slip over the threads on the container so that a tight rigid seal cannot always be 20 obtained by this type of cap.

The cap comprising the present invention is a quick-thread type cap wherein the lugs are formed from excess metal which is forced inwardly in such manner that the 25 lugs are under compressive forces which resist any tendency to force the lug outwardly, particularly in view of the fact that the continuous smooth rolled edge extends immediately over and reinforces each and all of the 30 projections. By actual experiment it has been found substantially impossible to "strip" these projections over the container threads so that by means of this cap it is possible to provide a very tight effective 35 closure. Since the wire or rolled edge of the cap is symmetrical and covers the inwardly extending lugs the cap presents a perfectly symmetrical and pleasing appearance.

This cap may be formed in various ways, 40 but preferably is formed of ductile sheet material by punching and spinning operations.

Referring now to the drawings, in Fig. 1 is illustrated a form of blank 1 which is 45 substantially circular with the exception of extensions 2 which in the present case are located uniformly at 90 degrees around the periphery of the blank. In Fig. 2 the blank has been cupped to provide a cover portion 50 which may contain an ornamental bead 5. A skirt 6 is integral with and extends from the cover portion 4 and carries the remainder of the blank which comprises the flange 7. It will be noted that the excess metal or 55 extensions 2 are maintained in the flange at this time. The operations illustrated in Figs. 1 and 2 may be accomplished by a single stroke of a suitable press. The blank as shown in Fig. 2 may next be operated 60 upon by a suitable spinning mechanism which may comprise a blank carrying head 8 having a shoulder 9 adapted to come adjacent the edge of the skirt, and a spinning head 10 adjacent which is a guide plate 11 65 and a second spinning head 12. A movable

member 14 may be suitably mounted upon the boss 15, and preferably is urged inwardly by the spring 16 controlled by the check nuts 17. As the cap carrying head 8 is brought into engagement with the spinning heads 10 70 and 12 the edge of the flange 7 contacts with the spinning roll 12, and as the spinning rolls are yieldingly forced together the rotation of these rolls and the pressure on the edge of the flange 7 gradually causes the excess metal to be driven inwardly and to loop upon itself as at 18 (Fig. 3). The member 14 co-operates with the other spinning heads to shape the flange. The cap thus formed has the substantially circular annular skirt portion with portions of the metal folded inwardly and outwardly across the lower margin thereof as is shown in Fig. 4, whereby the segmentally shaped thread engaging lugs 19 are formed upon the interior 80 of the cap. The next operation rolls the flange 7 into a wire edge 20 which is continuous around the entire lower edge of the skirt. Preferably the side wall of the skirt is knurled as at 21 in order to provide suitable grips for applying or removing the cap. 90

In a cap of this construction the segmental lugs 19 may be made of sufficient length to operate effectively on containers having inclined lugs, and to operate also upon containers equipped with spiral threads. The lugs, the metal therein having been shaped under compression, will be particularly strong, and said lugs being of tubular form, they will exercise a very material stiffening 100 and strengthening influence on the cap across the areas where the seating pressure is applied. Moreover, the skirt is held against circumferential expansion by the bead 22, so that the lugs can not be stripped 105 over the threads, and the appearance of the closure is symmetrical, unbroken, and pleasing.

I claim—

1. As an article of manufacture a bottle 110 cap comprising a cover portion, a skirt depending from said cover portion, a thread-engaging projection formed under compression adjacent the lower edge of the skirt, and a continuous rolled edge on the lower 115 edge of the skirt and covering the said projection.

2. As an article of manufacture a bottle cap comprising a cover portion, a skirt 120 inwardly extending thread engaging lug formed under compression adjacent the lower edge of the skirt, and a continuous rolled bead on the lower edge of the skirt and covering the concavity of said thread 125 engaging lug on the exterior of the cap.

3. As an article of manufacture a closure cap comprising a cover portion, a skirt depending from said cover portion, and a locking projection comprising metal folded 130

upon itself at the lower edge of the skirt portion and extending inwardly at substantially right angles to said skirt portion, the upper fold being integral with the skirt portion and the lower fold extending across the lower limit of the skirt portion.

4. As an article of manufacture a closure cap comprising a cover portion, a skirt depending from said cover portion, and a hollow segmental locking projection comprising metal folded upon itself at the lower edge of the skirt portion and with the upper side of the projection extending inwardly at substantially right angles to said skirt

15 portion.

5. As an article of manufacture a closure cap comprising a cover portion, a skirt depending from said cover portion, and a plurality of lugs arranged at the lower edge 20 of the said skirt portion comprising metal extending across the margin of the skirt and folded upon itself and rolled outwardly into a wire edge on the lower edge of the said skirt.

25 6. As an article of manufacture a closure cap comprising a cover portion, a skirt depending from said cover portion, and a plurality of lugs arranged at the lower edge of the said skirt portion comprising metal 30 folded inwardly and outwardly across the skirt and with the lower fold of the said metal terminating in a wire edge located at the lower edge of the said skirt.

7. As an article of manufacture a closure 35 cap comprising a cover portion, a skirt depending from said cover portion, and a plurality of closed tubular lugs at the lower edge of said skirt.

8. As an article of manufacture a closure 40 cap comprising a cover portion, a skirt depending from said cover portion, a plurality of inwardly extending lugs of segmental form at the lower edge of said skirt, and a wire roll edge comprising the free edge of 45 the skirt and covering and supporting the said lugs whereby the lugs are invisible from the exterior of the cap when the cap is in position upon a suitable vessel.

9. As an article of manufacture a closure 50 cap comprising a cover portion, an annular skirt depending from said cover portion, a continuous smooth bead on the lower edge of said skirt, and projections extending inwardly from said bead and comprising the

metal folded upon itself and retained under 55 compression by the bead at substantially a right angle to the said skirt.

10. As an article of manufacture a closure cap comprising a cover portion, an annular skirt depending from said cover portion, a 60 continuous smooth bead on the lower edge of said skirt, and projections extending inwardly from said bead and comprising the metal folded upon itself and at substantially 65 a right angle to the said skirt, and with the metal in the lower fold under greater compression forces than the metal in the upper fold.

11. A closure cap of the character specified comprising a cover portion, an annular 70 skirt depending from said cover portion, a plurality of lugs adjacent the edge of said skirt and comprising segments of metal folded upon itself and integral with the skirt throughout their length. 75

12. A closure cap of the character specified comprising a cover portion, an annular skirt depending from said cover portion, a plurality of lugs adjacent the edge of said skirt and comprising elongated segments of 80 metal folded upon itself and compressed at substantially a right angle to the wall of the skirt and with the metal in the lower fold having greater compression than the metal in the upper fold. 85

13. A closure cap of the character specified comprising a cover portion, an annular skirt depending from said cover portion, a plurality of lugs comprising folds of metal 90 extending inwardly on the lower edge of the said skirt portion and outwardly across the edge thereof, and a smooth rolled wire edge extending around the said skirt and comprising a support tending to resist forces against the inner edges of the said lugs. 95

14. A closure cap of the character specified comprising a cover portion, an annular skirt depending from said cover portion, a continuous annular bead formed at the lower margin of the skirt portion, a plurality of 100 elongated thread engaging lugs extending substantially perpendicular to the skirt portion, each of said lugs comprising an upper fold connecting with the skirt portion and a lower fold connecting with the annular 105 bead.

FREDERICK G. WIELAND.
